UNITED STATES PATENT OFFICE.

PAUL E. SCHLEICHER, OF CHICAGO, ILLINOIS.

DESIGN FOR A RADIATOR COVER.

Application filed July 3, 1924. Serial No. 10,042. Term of patent 14 years.

To all whom it may concern:

Be it known that I, PAUL E. SCHLEICHER, a citizen of the United States, residing at Chicago, Cook County, Illinois, have invented a new, original, and ornamental Design for a Radiator Cover, of which the following is the specification, reference being had to the accompanying drawing, forming a part thereof.

Figure 1 is a front view of the radiator cover.

Figure 2 is an end view of the radiator cover.

I claim:

The ornamental design for a radiator cover as shown.

PAUL E. SCHLEICHER.

Witnesses:

CHARLES W. HILLS, Jr.,
